CLAIM

The ornamental design for a housing for a communication device, as shown and described.

DESCRIPTION

FIG. 1 is a perspective view of a first embodiment of an ornamental design for a housing for a communication device.

FIG. 2 is a front view of the first embodiment thereof.

FIG. 3 is a rear view of the first embodiment thereof.

FIG. 4 is a first side view of the first embodiment thereof.

FIG. 5 is a second side view of the first embodiment thereof.

FIG. 6 is a top view of the first embodiment thereof.

FIG. 7 is a bottom view of the first embodiment thereof.

FIG. 8 is a perspective view of a second embodiment of an ornamental design for a housing for a communication device.

FIG. 9 is a front view of the second embodiment thereof.

FIG. 10 is a rear view of the second embodiment thereof.

FIG. 11 is a first side view of the second embodiment thereof.

FIG. 12 is a second side view of the second embodiment thereof.

FIG. 13 is a top view of the second embodiment thereof.

FIG. 14 is a bottom view of the second embodiment thereof.

FIG. 15 is a perspective view of a third embodiment of an ornamental design for a housing for a communication device.

FIG. 16 is a front view of the third embodiment thereof.

FIG. 17 is a rear view of the third embodiment thereof.

FIG. 18 is a first side view of the third embodiment thereof.

FIG. 19 is a second side view of the third embodiment thereof.

FIG. 20 is a top view of the third embodiment thereof; and,

FIG. 21 is a bottom view of the third embodiment thereof.

The broken lines shown in FIGS. 1-7 and 15-21 that are immediately adjacent to the shaded areas and define unshaded regions, represent the bounds of the first and third embodiments respectively, while all other broken lines are directed to environment and are for illustrative purposes only; the broken lines form no part of the embodiment in which they are shown.
